United States Patent Office

Des. 196,342
Patented Sept. 17, 1963

196,342

CANOE

Robert M. Taft, Coon Rapids, and John Sawicki, Minneapolis, Minn., assignors of one-half to said Robert M. Taft, Coon Rapids, and one-half to Warren R. Taft, South Haven, Minn.

Filed Nov. 1, 1960, Ser. No. 62,700

Term of patent 14 years

(Cl. D71—1)

We claim:

The ornamental design for a canoe, substantially as shown.
